RIMMED STRUCTURE

Earl C. Bullock, Grand Rapids, Mich., assignor
to Metal Office Furniture Company, Grand
Rapids, Mich., a corporation of Michigan

Application August 13, 1937, Serial No. 158,899

7 Claims. (Cl. 220—73)

The present invention relates to rimmed structures and more particularly to a receptacle having novel structural features and to the method of assembling the several parts of a receptacle such as a waste basket or the like.

The primary objects of the instant invention are to provide a structure such as a waste basket or other similar receptacle having a resilient rim of rubber or the like; to provide such a device whose resilient rim is secured to the structure in a novel manner; to provide such a structure whose parts may be readily, conveniently and economically assembled together; and, to provide a receptacle or similar structure which is attractive in appearance and utilitarian in use.

An illustrative embodiment of the invention is shown in the accompanying drawing, wherein:

Figure 1 is an elevational view of a waste basket, a portion of whose side wall has been broken away to better show its structural details;

Figure 2 is a top plan view thereof, a portion of its bottom and portions of its rim being broken away to better show its constructional features;

Figure 3 is an enlarged sectional view of a portion of the rim construction of the invention;

Figure 4 is a view similar to Figure 3 but showing an element of the rim prior to being pressed into assembled relation with its resilient element;

Figure 5 is an enlarged fragmentary perspective view of the corner portion of the waste basket shown in Figures 1 and 2.

Referring then to the drawing wherein like parts of the structure shown are designated by the same numerals in the several views, a waste basket provided with the rim of the instant invention and having other novel structural features comprises pairs of oppositely spaced upwardly angularly disposed side walls 10 of stamped sheet metal or the like secured together adjacent their marginal sides to cross-sectionally arcuate stamped sheet metal corner members 11 as by spot welding.

The corner members are provided with ball feet 12 and the upper ends of the side walls 10 together with the upper ends of their securing corner members 11 are provided with outwardly and laterally flanged portions 13 which prior to their assembly with the rim elements of the structure have a downwardly angularly formed portion 14 (Figures 4 and 5) and a vertically extending portion 15 as shown in Figure 4.

Seated upon and secured to the laterally flanged portions 13 of the side walls 10 and cor-

ner members 11 as by spot welding is a channel rim element, generally designated 16 having parallel flanged portions or legs 17, 18. A resilient rim element 19 of rubber or the like is provided with a groove 20 within which the leg 17 is seated and with a groove 21 within which the vertically extending portion 15 of each side wall and of each corner member is pressed from its position shown in Figure 4 to the position shown in Figure 3.

The lower end of each side wall 10 is provided with an inwardly and laterally flanged portion 22 upon which the metal bottom 23 of the receptacle is supported and to which it is secured as by spot welding.

The resilient element 19 may be of a length sufficient to be wrapped onto the channel rim element 16 but it is preferably endless and stretched into assembled relation with the channel rim element.

It is to be noted that the resilient rim element when thus assembled projects both laterally and vertically beyond the peripheral edges of the legs 17, 18 of the channel rim element 16 and outwardly beyond the upwardly angularly disposed side walls of the waste basket. Marring of furniture and walls is thus prevented by contact of the resilient rim therewith and a cushioning effect on the structure as a whole is provided by the upper projecting portion of the resilient rim when the basket is up-ended and thrust downwardly against the rim of a waste hopper or the like in emptying the basket.

It will thus be seen that the structure of the instant invention and particularly the constructional character of its rim and method of assembly thereof is not only novel but is likewise utilitarian in use, economical in manufacture and attractive in appearance.

While but one specific embodiment of the invention has been herein shown and described, it will be understood that certain details of the construction shown may be altered or omitted without departing from the spirit of the invention as the same is defined by the following claims.

I claim:

1. A receptacle whose wall is laterally flanged at its upper edge to provide a rim support and again flanged upwardly to provide a rim securing portion, a channel rim element having one leg thereof supported upon said rim support and the other leg thereof extending at substantially right angles to the upwardly extending flange, and a resilient rim element having one groove

within which the last mentioned leg of the channel rim element is seated and having another groove within which said rim securing portion is seated.

5. 2. In a receptacle, spaced upstanding corner members, upstanding side walls secured adjacent their marginal sides to said corner members, said corner members and said side walls each having laterally extending rim supporting portions on the upper ends thereof, vertical flanges on said rim supporting portions, a channel rim element having one leg thereof supported upon said rim supporting portions, and a resilient rim element having one groove within 15 which the other leg of the channel rim element is seated and having another groove within which the upstanding flanges on said rim supporting portions are seated, said resilient rim element having surface portions extending upwardly beyond the channel rim element and outwardly beyond the rim supporting portions of 20 said side walls and said corner members.
3. In a receptacle, spaced upstanding corner members upstanding side walls secured adjacent 25 their marginal sides to said corner members, said corner members and said side walls each having laterally extending rim supports on the upper ends thereof and each of said rim supports having a portion bent angularly downwardly prior to 30 assembly of the receptacle and having a flange extending vertically from said angularly bent portion, a channel rim element having one leg thereof supported upon said rim supports, and a resilient rim element having one groove within 35 which the other leg of the channel rim element is seated and having another groove receiving said vertically extending flanges subsequent to the upward bending of the downwardly angularly 40 bent portions of said rim supports during assembly of the receptacle.
4. A receptacle whose wall is laterally flanged at its upper edge to provide a rim support and again flanged upwardly to provide a rim securing portion, a channel rim element having one leg 45 thereof supported upon said rim support and the other leg thereof extending at substantially right angles to the upwardly extending flange, and an endless resilient rim element having one groove within which the last mentioned leg of the chan-

nel rim element is seated and having another groove within which said rim securing portion is seated.

5. A receptacle whose wall is laterally flanged at its upper edge to provide a rim support and again flanged upwardly to provide a rim securing portion, a channel rim element having one leg thereof supported upon said rim support and the other leg thereof extending at substantially right angles to the upwardly extending flange, and a resilient rim element having one groove within which the last mentioned leg of the channel rim element is seated and having another groove within which said rim securing portion is seated, said resilient rim element having a surface portion extending beyond the legs of the channel rim element and beyond the flanged portion of the rim supporting member. 10

6. A receptacle having an upstanding side wall provided with a laterally extending rim support on the upper end thereof, said rim support having a portion bent angularly downwardly prior to assembly of the receptacle and having a flange extending vertically from said angularly bent portion, a channel rim element having one leg thereof supported upon said rim support, and a resilient rim element having one groove within which the other leg of the channel rim element is seated and having another groove receiving said vertically extending flange subsequent to the upward bending of the downwardly angularly 20 bent portion of said rim support during assembly of the receptacle. 25

7. In a receptacle, spaced upstanding corner members, upstanding side walls secured adjacent their marginal sides to said corner members, said corner members and said side walls each having laterally extending rim supporting portions on the upper ends thereof, vertical flanges on said rim supporting portions, a channel rim element having one leg thereof supported upon said rim supporting portions, and a resilient rim element having one groove within which the other leg of the channel rim element is seated and having another groove within which the upstanding flanges on said rim supporting portions are seated. 30 35 40 45

EARL C. BULLOCK.
